UNITED STATES PATENT OFFICE.

ALFRED OBERLE, OF OAK PARK, ILLINOIS, ASSIGNOR OF ONE-HALF TO THOMAS E. SCOFIELD, OF KANSAS CITY, MISSOURI.

METHOD OF PURIFYING AND DECOLORIZING PETROLEUM HYDROCARBONS.

No Drawing.

Application filed December 1, 1924. Serial No. 753,345.

This invention relates to improvements in the decolorizing of petroleum hydrocarbons and relates more particularly to the purifying, refining and decolorizing of lighter oils or distillates, such as those recovered from distillation, either under pressure or atmospheric conditions. Distillates recovered by vacuum distillation can be as well treated as those recovered under pressure. 5
10 It has been found that distillates such as those above mentioned, and particularly the lighter oils recovered from the decomposition of petroleum by pressure distillation are very apt to be discolored by exposure 15 to light and air. This tendency is particularly noticeable where gasoline is exposed in visible pumps to the sun's rays. Such dis- 20 coloration is objectionable to the marketing of the motor fuel.
Numerous methods and processes have 25 been attempted to eliminate this objectionable discoloration and to a considerable extent the action of the light rays upon the oil has been retarded. Processes such as 30 steam distillation, repeated treatments with acid and caustic, sulphur dioxide, sodium plumbite, fuller's earth, charcoal filters, silica gel, etc., and other methods have eliminated, to a considerable extent, this tendency to 35 discolor. There has, however, been no satisfactory method which will do away entirely with the discoloring of the oil and also prevent the action of the light prior to the time that the discoloration takes place.
It has been found that when a distillate is 40 treated or washed with an aqueous solution containing potassium iodide that the distillate upon exposure to light or air will take on an orange or pinkish hue. On separation from the aqueous solution, the distillate is

filtered, at which time the color is substantially removed; with a subsequent water wash the resulting product is water white and remains so even though exposed to direct sunlight. 45

The aqueous solution containing potassium iodide, separated from the distillate, may be reused or the salts separated by crystallization and redissolved in a fresh solution. There may be a small amount of the salts 50 recovered from the filter through which the distillate was passed, or, instead of the salts, the material recovered may be in the form of other iodine compound. Satisfactory results have been obtained by the use of potassium iodide employed as the water soluble material. 55

A factor of importance in connection with the treatment, is that a hydrocarbon distillate combined with an aqueous solution containing iodine compounds may apparently give no reaction when the combination or mixture is made in a darkened room or receptacle. It has been found that light, and particularly the direct sunlight, has an activating effect upon the reaction, producing the discoloration in the form of an orange or pinkish hue to develop in the mixture soon after their combination. Evidently, light has the effect of bringing about or 60 activating the reaction which takes place. 65

I claim as my invention:

A process for decolorizing and purifying petroleum hydrocarbons, consisting in contacting the oil with a treating solution containing potassium iodide, permitting the oil and treating solutions to separate, and separating the treated oil from the treating material by filtration. 75

ALFRED OBERLE.
